US00D583374S

(12) **United States Design Patent**
Otsuka

(10) **Patent No.:** **US D583,374 S**
(45) **Date of Patent:** **** Dec. 23, 2008**

(54) **RECORDING MEDIUM**

(75) Inventor: **Hitoshi Otsuka**, Yokosuka (JP)

(73) Assignee: **Kabushiki Kaisha Toshiba**, Tokyo (JP)

(**) Term: **14 Years**

(21) Appl. No.: **29/297,868**

(22) Filed: **Nov. 20, 2007**

(30) **Foreign Application Priority Data**

Jun. 5, 2007 (JP) 2007-014884

(51) **LOC (8) Cl.** **14-02**

(52) **U.S. Cl.** **D14/356**

(58) **Field of Classification Search** D14/411, D14/384-385, 518, 348, 432-436, 299, 167, D14/402, 242, 356, 358, 496, 156, 240; 455/344; 710/300-301; 361/684-686; 439/518, 139-141, 439/131, 607, 133; 365/63
